Primary Examiner—Doris V. Coles[57] **CLAIM**

The ornamental design for a fishing lure, as shown and described.

DESCRIPTION

FIG. 1 is a top plan view of a fishing lure showing my new design;

FIG. 2 is a left side elevational view, the right side elevational view being identical;

FIG. 3 is a cross-sectional view taken along line 3—3 of FIG. 1;

FIG. 4 is a bottom plan view; and,

FIG. 5 is a perspective view.

Broken lines in FIGS. 1-5 show unclaimed subject matter [fishhook] and is included for illustrative purposes only and form no part of the claimed design.
